UNITED STATES PATENT OFFICE.

RICHARD B. DOUGLAS, OF NEW YORK, N. Y.

PROJECTILE.

SPECIFICATION forming part of Letters Patent No. 336,556, dated February 23, 1886.

Application filed April 12, 1884. Serial No. 127,607. (No model.)

To all whom it may concern:

Be it known that I, RICHARD B. DOUGLAS, a citizen of the United States, residing in the city, county, and State of New York, have 5 invented a new and useful Improvement in Projectiles, of which the following is a specification.

My invention relates to projectiles to be used in various descriptions of fire-arms and 10 guns of whatever caliber, the object being to provide for greater accuracy in forcing the projectile through the atmosphere, either against or transversely to a strong wind, more especially at long range. I attain this object by 15 means of the contrivance illustrated in the accompanying drawings, in which—

Figure 1 is a horizontal view of my cartridge as it appears when complete and ready to be inserted into the cartridge-chamber of 20 the piece. A is the cartridge-shell, being of the description now in ordinary use. B is that portion of the projectile which extends beyond the shell. B' is the exposed part of the metallic steering or guiding rod, which 25 passes through the projectile B longitudinally. b' is the front head-piece of the rod B'.

Fig. 2 is a sectional view of the different parts of the cartridge, showing the different 30 features of my invention. A represents the shell; A', the vacant space in the fore part of the shell, into which the projectile B is inserted. A' is a view of the cover or wad of the powder-charge, upon which the projectile rests. a is a cavity or recess in the cover or wad A', 35 into which the burr or rivet, formed at the rear extremity of the guiding-rod B', is seated in such manner that the whole force of the charge is exerted upon the projectile proper at points sufficiently beyond its center to prevent 40 the forcing of the guiding-rod into its base. B is the projectile proper, showing the passage of the guiding-rod longitudinally through its center. B' shows the position of the guiding-rod after the discharge of the explosive within the cartridge-shell. B' is a 45 flexible button or other attachment placed upon the rear extreme of the guiding-rod B', and answering the same purpose as the feathered attachment of an arrow. This button or 50 its equivalent may be made of any suitable material and of any desired form. b is the burr or rivet at the rear extremity of the guiding-rod B', to prevent the detachment or sliding off of the button B' in the passage of

the projectile upon or after its discharge. It 55 will be observed that the guiding-rod B' is so constructed as to play loosely within the projectile B, and that immediately upon the projectile being discharged from the shell A, the rod shifts its position and is drawn backward 60 through the projectile, so as to bring the pointed cap b' down upon the pointed end of the projectile B, thus giving the projectile proper a metallic point. At the base of the projectile B there is formed a recess corresponding in size to the button B', so that when the cartridge is formed complete the button B' is held within the recess against the base of the projectile, and the cavity a in the shell cover or wad A' is intended to receive the 70 burr or rivet b merely.

Fig. 3 is a perpendicular projection of the front end of the shell proper, A, showing the wad A' with the central recess, a, therein.

Fig. 4 is a perpendicular projection of the 75 base of the projectile proper, B, showing the recess at B' for the reception of the flexible button, or its equivalent, and the orifice B', for the reception of the rod B'.

The materials used in constructing the cartridge are of the ordinary kind now in use, 80 and may be varied accordingly, as desired, for guns and pieces of large and small caliber.

I am aware that prior to my invention various devices have been used to insure accuracy in the use of projectiles, particularly in 85 respect to torpedoes; but I am not aware that any device similar to that embraced in my invention has ever been suggested or employed in connection with projectiles discharged from 90 the chamber of a rifle or gun barrel.

I am also aware that the combination of the charged metallic shell and projectile proper to be used in arms of various kinds is not new. I therefore make no claim for such combination; but 95

What I do claim as my invention, and desire to secure by Letters Patent, is—

The combination of a rifle or gun projectile formed with a sliding and revolving rod 100 or axis having a flexible burr or feather at its rear extreme, with the metallic cartridge-shell, substantially as and for the purpose specified.

RICHARD B. DOUGLAS.
